FREDERICK B. MEYERS AND HARRY W. DARNEY, OF BALTIMORE, MARYLAND, AS
SIGNORS OF ONE-HALF TO REGINALD BRAGONIER, OF BALTIMORE, MARYLAND.

ERASER CLEANER.

Application filed July 12, 1927. Serial No. 205,239.

At the present time blackboard erasers are customarily cleaned by merely beating the same against some fixed surface, the chalk dust which has been absorbed by the felt 5 or other soft rubbing face of the eraser being thereby caused to fly out into the open air so that it is exceedingly apt to be breathed by the person cleaning the eraser and by other pupils or persons in the room. 10 This method is obviously unsanitary and unhealthful, and it is the object of the present invention to provide a simple and inexpensive device whereby blackboard erasers may be very effectually and rapidly cleaned and 15 the dust confined so that it will not blow about and cannot contaminate the air within the school room. The object of the invention is attained in such a device as is illustrated in the accompanying drawing, and the invention resides in certain novel features which 20 will be hereinafter first fully described and then more particularly defined in the appended claims.

In the drawing:

25 Figure 1 is a central vertical longitudinal section of an eraser cleaner embodying our invention;

Fig. 2 is a transverse section on the line 2-2 of Fig. 1, and

30 Fig. 3 is a detail plan view of the grating or scraper by the action of which the dust is loosened from the eraser.

In carrying out the invention, there is provided a container comprising a box or 35 body 1 of oblong form which is adapted to be firmly secured upon a fixed support, the drawing showing the box as provided with a base 2 having its edge portions projecting beyond the sides and ends of the box and 40 formed with openings 3 therethrough for the insertion of screws or other fastening devices into any convenient fixed support. The container also includes a cover 4 which is connected by hinges 5 at one side to the top of the box and at the other side is held closely thereto by a clasp 6 of any approved type, the cover being thereby held firmly to the box so that the dust from the eraser will be held within the box and cannot escape into 45 the open air. In the sides of the box above the bottom thereof are provided cleats or rails 7 which form horizontal guides for a scraper 8 consisting of an open frame fitting rather closely between the sides of the box 50 and provided in its sides with longitudinal

grooves engaging slidably with the projecting edges of the cleats 7, as clearly shown in Fig. 2. Fitted in the open frame are a plurality of transverse slats or blades 9, the upper edges of which project slightly above 55 the upper surfaces of the sides and ends of the frame, and these slats are spaced apart, as shown in Figs. 1 and 3, so that open passages for the dust is provided. To one end of the frame 8 is secured a rod 10 extending therefrom through an opening provided therefor in the end of the box and equipped beyond the box with any convenient form of handle 11. Obviously by grasping the handle 11 the scraper frame 8 may be reciprocated along the cleats 7 so that the upper edges of the slats 9 may rub across the surface of an eraser presented thereto and thereby so agitate the surface that it will be spread somewhat and the chalk dust separated therefrom. Below the scraper a drawer or tray 12 is fitted closely within the box to rest upon the bottom of the same and 60 one end of this tray or drawer is provided with a head 13 fitting closely within an opening provided therefor in the end of the box opposite the handle 11 so that the opening in the box will be closed but the drawer or tray may be easily withdrawn when it is desired to remove the dust collected therein. 65 The head 13 is provided with a cap plate 14 bearing against the outer side of the box around the opening and this cap plate is equipped with a handle 15 of any convenient form. A latch 16 may be provided to hold 70 the drawer against accidental withdrawal and also to hold the cap plate 14 over the opening in the end of the box so as to resist leakage of the dust. 75

The eraser 17 is mounted in the cover of the container below a plunger 18 so that pressure exerted upon the plunger will hold the eraser to the scraper while the latter is reciprocated. The plunger comprises a plate 18 and a stem or rod 19 firmly secured thereto and rising therefrom through the top of the cover, an expansion spring 20 being coiled around the plunger rod or stem 19 between the cover and a knob or handle 21 at the upper end of the plunger rod, as 80 shown, whereby the plunger will be normally held in its raised position and will release the eraser when the pressure thereon has been withdrawn. To hold the eraser 85 against movement transversely or longitudi- 105

nally of the cover, the side members of the cover are of such dimensions or so spaced that they will accommodate the eraser between them but will prevent any excessive movement laterally of the eraser which would permit it to shift to one side of the scraper. Extending between the side members of the cover is a bar or stationary clamping member 22 against which one end 10 of the eraser may abut, as shown in Fig. 1, and in the lower edge of this clamping member is a notch 23 to facilitate the insertion or removal of the eraser. The opposite end of the eraser is engaged by a movable clamping 15 jaw 24 fixed upon the end of a rod 25 which extends therefrom toward the adjacent end of the cover and is slidably mounted in the inner end wall of a chamber or case 26, the outer end of said rod being equipped with a 20 piston 27 within said chamber and an expansion spring 28 being housed within the chamber between the piston and the outer end wall of the cover, as clearly shown in Fig. 1, so that the force of the spring is exerted constantly to project the abutment or 25 clamping jaw 24 against the eraser and thereby hold the eraser against the stationary clamping member 22.

The use of the device will, it is thought, be 30 clear from the foregoing description, taken in connection with the accompanying drawing. When an eraser is to be cleaned, the lid or cover of the box is swung over to open position and the eraser is then inserted between the clamping members 22 and 24 by 35 pressing one end of the eraser against the movable clamping jaw 24 and then pushing the eraser between the two clamping elements. The spring 28 will then hold the 40 eraser firmly between the clamping elements as previously described. The cover is then returned to closed position and pressure is exerted downwardly upon the plunger rod 19 so that the eraser will be pressed against 45 the scraper, and the scraper is reciprocated by manipulation of the handle 11 and rod 10 in an obvious manner. The upper projecting edges of the several scraper slats 9 will 50 have a beating action upon the surface of the eraser so that the dust collected therein will be loosened and will fall through the spaces between the slats into the drawer or tray 12. The operation of the device for a 55 very short period of time will thoroughly clean the eraser and after one eraser has been cleaned it is removed and another eraser inserted, the operation being repeated until all 60 of the erasers on hand have been cleaned. While ordinarily the device will be made to 65 accommodate a single eraser, it will be obvious that it may be made in such dimensions as to accommodate two or more erasers at one time and, of course, may be made in various dimensions according to the sizes of 70 the erasers which are in use.

The device is very compact and is free of complicated arrangements or constructions so that it may be easily manipulated and will not be apt to get out of order.

Having thus described the invention, we 70 claim:

1. An apparatus for the purpose set forth comprising a container constructed to admit an eraser, means for mounting an eraser within the container, a reciprocable scraper 75 fitted within the container to act upon an eraser mounted therein, means for closing the container around the eraser, and means for pressing the eraser against the scraper.

2. An apparatus for the purpose set forth comprising a container, means for releasably supporting an eraser therein, a scraper mounted slidably within the container in position to act upon the eraser and having discharge openings through its bottom whereby 85 dust from the eraser may pass freely therethrough, means whereby an eraser may be held against the scraper, means for closing the container around the eraser and the scraper, and a dust collector removably fitted in the container below the scraper. 90

3. An apparatus for the purpose set forth comprising a container, means for mounting an eraser within the container, a reciprocatory scraper mounted within the container 95 below the eraser and comprising an open frame and transverse slats secured in said frame in spaced relation with their upper edges projecting above the frame to impinge upon the eraser, means for closing the container around the eraser and the scraper, and means whereby the eraser may be held to the scraper. 100

4. An apparatus for the purpose set forth comprising a container, a scraper slidably mounted in the container, a handle element secured to one end of the scraper and projecting through the adjacent end of the container, yielding means for supporting an eraser over the scraper, means for closing the container around the scraper and the eraser, and means whereby an eraser may be held to the scraper. 105

5. An apparatus for the purpose set forth comprising a container, a reciprocatory scraper mounted therein, a fixed clamping element within the container above the scraper against which an eraser may abut, a movable clamping jaw cooperating with said fixed clamping member to hold an eraser, means 115 for yieldably projecting the movable clamping jaw toward the fixed clamping element, means for closing the container around the eraser and the scraper, and means between the clamping jaw and fixed clamping element to hold an eraser against the scraper. 120

6. An apparatus for the purpose set forth comprising a container, a reciprocatory scraper mounted in the container, means above the scraper for supporting an eraser, 130

means for closing the container around the eraser and the scraper, a plunger mounted in the container to bear upon the eraser, a plunger rod secured to the plunger and extending therefrom through the top of the container whereby pressure may be applied to hold the eraser to the scraper, and yieldable means acting on the plunger rod to normally retract the same.

7. An apparatus for the purpose set forth comprising a container, a reciprocatory scraper mounted within the container, a fixed clamping jaw in the container above the

scraper, a movable clamping jaw cooperating with the fixed clamping jaw whereby to secure an eraser inserted between the jaws, a rod extending outwardly from the movable clamping jaw, a piston on said rod, yieldable means acting on the piston to project the movable clamping jaw toward the fixed clamping jaw, and means for closing the container around the eraser and the scraper.

In testimony whereof we affix our signatures.

FRED. B. MEYERS. [L. S.]
HARRY W. DARNEY. [L. S.]
